PLATFORM TRAILER

Wylie A. Mason, Jr., 373 Dawson Drive,
Camarillo, Calif. 93010

Filed Mar. 26, 1969, Ser. No. 19,816

Term of patent 14 years

Int. Cl. D12—10

U.S. Cl. D14—3 E

FIG. 5

FIG. 4

FIG. 1 is a top plan view of the platform trailer showing my new design;

FIG. 2 is a side elevational view thereof;

FIG. 3 is a bottom plan view thereof;

FIG. 4 is a front elevational view thereof; and

FIG. 5 is a rear elevational view thereof.

The broken line showing of wheels in FIGS. 1, 2, 4 and 5 is for illustrative purposes.

I claim:

The ornamental design for a platform trailer, substantially as shown and described.
